Application September 13, 1945, Serial No. 616,055

2 Claims. (Cl. 179—2.5)

1

This invention relates to communication systems adapted for use by mobile units such as trains traveling along a railroad, or the like, wherein communication is established by inductive coupling between the mobile units and a transmission line or other conductive medium adjacent the right-of-way; and more particularly pertains to the provision of more effective inductive coupling in such systems.

It has been heretofore proposed to provide mobile units, such as trains, with communication apparatus of the type wherein the transmitting station modulates a carrier frequency signal which is supplied to a loop radiator or coupler to produce an electromagnetic field which acts to transfer signal energy to the line wires or other conductors extending more or less parallel to the right-of-way; and similarly, wherein the receiving station has a loop receiving coupler arranged to intercept the electro-magnetic field produced by the modulated carrier current signal energy induced in the transmission line or other conductors, which electro-magnetic field induces current in the loop and supplies an input to the receiver and demodulating organization. Thus, voice messages can be transmitted between the two mobile stations.

In providing systems of this character, it will be readily apparent that the degree of coupling between the loop couplers or antennas and the transmission line or other conductors along the right-of-way is very small and for this reason the organization should be made as efficient as possible. In accordance with the present invention, it is proposed to improve the transmitting and receiving organizations in such a way as to materially improve the inductive coupling characteristics and effect the maximum transfer of signal energy for the particular level of energy employed by the transmitter.

In a system of the type above described, the resistive characteristics of the transmission line and also the metal parts of the associated vehicle are in effect inserted as positive resistance into the inductively coupled circuits of the transmitter and receiver units. Under these conditions, there is usually an excessive value of positive resistance coupled into the circuits, thereby tending to reduce the efficiency of energy transfer both in transmission and reception. It is thus proposed in accordance with the present invention to cancel this excessive value of the coupled positive resistance by introducing a controlled value of negative resistance.

More particularly, it is proposed that the can-

2

cellation of positive resistance reflected into the inductive coupling unit may be obtained by the provision of the proper quantity of negative resistance supplied by a suitable generator of the negative resistance type.

Thus, it may be said that one of the objects of the present invention is to so increase the efficiency of energy transfer in systems of the character described that communication may be more effective and carried on over greater distances than heretofore considered feasible.

Other purposes and characteristic features of the present invention will be in part obvious, and in part pointed out, as the description of the invention progresses.

In describing the invention in detail, reference will be made to the accompanying drawing illustrating a transmitter unit and a receiver unit both constructed in accordance with the present invention and capable of providing improved transmission of intelligence between their respective stations by the inductive transfer of energy via an adjacent transmission line or other conductive medium.

For the purpose of simplifying the illustration and facilitating in the explanation, the various parts and circuits constituting the embodiment of the invention have been shown diagrammatically and certain conventional illustrations have been employed, the drawing having been made more with the purpose of making it easy to understand the principles and mode of operation, than with the idea of illustrating the specific construction and arrangement of parts that would be employed in practice. Thus, the various devices such as electron tubes, microphone, batteries, resistors, condensers, and the like, have been illustrated in a conventional manner using symbols rather than illustrating these devices in detail.

With reference to the drawing, a transmission line or other conductive medium is indicated at 1 as extending over a considerable distance. At the left hand side of the drawing, a mobile transmitter unit is illustrated as being inductively associated with the transmission line or other medium 1; while on the right hand side of the drawing a mobile receiver unit has been shown as inductively associated with the transmission line.

The mobile transmitter unit comprises in general an audio amplifier, a carrier frequency oscillator, a modulator adapted to modulate the carrier frequency in accordance with the principles

55 of frequency modulation by the audio messages

spoken into the conventionally illustrated microphone. The output of the modulator and any additional amplifier is supplied through suitable connections and condenser C to the control grid of a power amplifier designated PA in the drawings. The grid leak resistor R₁ is used to provide the bias and thus provide the amplitude of the input to the power amplifier PA. This power amplifier PA, which supplies the primary winding 2 of the transmitter coupler TC with the frequency modulated carrier signals, is illustrated as being a tetrode tube having a heater type cathode, a control grid, a screen grid and a plate. The screen grid is connected through condenser C₁ to the cathode in the usual way, and a variable condenser C₂ is used for tuning the output winding 2. Plate potential is supplied by a suitable plate source designated PS₁ and connected through a radio frequency choke RF₁. A by-pass condenser C₃ is connected between the upper terminal of the choke RF₁ to ground.

The transmitter coupler TC has windings 3 and 4 which act as the inductances of the tuned plate and grid circuits of an oscillator or regenerative amplifier OC. A variable condenser C₅ is connected across these inductances and a condenser C₄ connects one terminal of the tuned tank circuit to the grid of oscillator tube OC while the grid is connected through a resistor R₂ to ground. The value of this resistor R₂ determines the amount of bias normally on the grid of the tube OC and thus limits the amplitude of oscillation in accordance with its value. Resistor R₄ provides adjustable control of the total negative resistance available in the output.

The plate potential is supplied to the tube OC by a suitable plate source designated PS₂ and connected through a radio frequency choke RF₂ to a point between the windings 3 and 4. A by-pass condenser C₆ is also connected from the midpoint between windings 3 and 4 to ground to complete the circuit to the cathode for the tuned plate and grid circuits.

An output or secondary winding 5 of the transmitting coupler TC is connected to a transmitting loop 6, which in practice will have a plurality of turns although only one has been indicated in the drawing. Also, this transmitting loop 6 is relatively large so as to produce as much inductive coupling with the wayside conductors as possible in spite of the substantial intervening space.

The mobile receiver unit includes a receiving loop 11 which is similar to the transmitting loop 6 since it includes a plurality of turns and is of substantial size so as to produce as much inductive coupling as is possible considering the space between the receiving loop 11 and the wayside conductors represented at 1. The receiving loop 11 is connected in series with an input winding 12 on the receiving coupler RC.

A regenerative amplifier including a pentode electron tube RA is inductively coupled to the receiving coupler RC by windings 13 and 14 having a common connecting tap forming a connection to the cathode of the amplifier tube RA. The upper terminal of winding 13 is connected to the control grid of tube RA, while the lower terminal of winding 14 is connected through condenser C₇ and variable resistor R₃ in multiple to ground.

A variable condenser C₈ is connected across the windings 13 and 14 of the receiving coupler RC to produce a resonated or tuned circuit for the regenerative amplifier RA which is of course

tuned for the carrier frequency signals to be received over the line conductors. The screen grid of the regenerative amplifier RA is connected to ground through the condenser C₁₀ and to the positive high voltage, through resistor R₅, while the suppressor grid is connected to the cathode in the usual way. Plate potential is provided from a suitable plate supply PS₃, but is bypassed for the carrier frequency by a suitable condenser C₉.

An output winding 15 of the receiver coupler RC is connected to supply the received carrier signals as modified by the regenerative amplifier RA to a conventional carrier frequency amplifier, demodulator and audio amplifier, so as to supply a conventional loud speaker with audio signals in accordance with the messages spoken into the microphone of the mobile transmitter unit.

It is, of course, to be understood that the mobile transmitter and receiver units are suitably located within the particular vehicles with which they are associated, and for this reason, the transmitting and receiving loops will have to be connected by suitable lead-in wires to their respective transmitter and receiver units. The mountings of the loops 6 and 11 are preferably in free spaces with respect to the trains or other mobile units carrying them. It should also be understood that the various devices associated with the transmitter and receiver units are intended to be of conventional character, and the disclosure has been considerably abbreviated in order to more clearly illustrate the organization forming the present invention.

It is believed that the characteristic features of the present invention will best be understood by further description being given from the standpoint of operations and functioning of the various units.

Referring to the drawing, it will be noted that the power amplifier PA in effect acts as a generator or source of power which is inductively coupled through the primary winding 2 of the transmitting coupler TC to the secondary winding 5 supplying energy to the transmitting loop 6. The loop 6 with its plurality of turns forming the loop is inductively coupled through electromagnetic lines of induction produced therein with the transmission line 1 or other conductive medium located along the roadway. Thus, the carrier signal produced by the power amplifier PA, and modulated with any desired voice message in accordance with the principles of frequency modulation, is inductively supplied to the transmitting medium along the roadway. The signals thus produced in the transmission line travel for considerable distances due to the relatively good conducting characteristics of such line or lines.

These modulated carrier signals, throughout the territory or range of transmission, may be picked up by one or more mobile receiver units by reason of the inductive coupling of the receiving loop of each receiver unit with the transmission line. The energy thus received by a mobile unit is supplied inductively to the input winding of the carrier frequency amplifier, demodulator and audio amplifier apparatus of the receiver.

In the above brief description of the operation of the communicating organization, the functioning of the regenerative amplifier or oscillator OC and the regenerative amplifier RA has been omitted. This has been done for two

reasons, namely, because their action is a modifying action on the transmission and reception and also because it is convenient to discuss the general principles of the basic functioning of the system before considering such modifying action in detail.

More specifically, it will be well understood by those skilled in the art, that the electrical characteristics of the transmission line 1, the transmitting loop 6 and the output winding 5 will be reflected into the output circuit of the power amplifier PA, the same as if an equivalent impedance were inserted serially in the plate circuit of the power amplifier PA. In order for the power amplifier PA to effect the greatest transfer of energy to its load circuit, the sum of the impedance of its output circuit including the reflected impedances from the secondary circuits, and the impedances of the primary winding 2, must be matched with the impedance of the amplifier PA. Although this matching of impedances in the output circuit of the power amplifier may effect the maximum current flow in the primary winding 2, it is also essential that the resistance characteristics of the various circuits involved shall have the proper values in order to obtain the maximum transfer of energy to the wayside line 1. This is because of the conditions involved in establishing the conditions of critical coupling for the maximum transfer of energy from a primary winding to a secondary winding in a resonated circuit.

For a complete discussion of critical coupling reference may be made to Terman's Radio Engineers' Handbook, pages 155 to 156. However, for the purposes of the present description, it is sufficient to understand that the maximum transfer of energy between the primary and secondary windings of a transformer at resonant frequency is dependent both upon the actual mutual coupling between the windings and the matching of the primary and secondary resistances. This is expressed by the equation

$$\frac{(2\pi f M)^2}{R_s} = R_p$$

Since

$$Q_p = 2\pi \frac{f L_p}{R_p}; Q_s = 2\pi \frac{f L_s}{R_s}; \text{ and } K = \frac{M}{L_p L_s}$$

Therefore, critical coupling is expressed by the equation

$$K_c = \frac{1}{\sqrt{Q_p Q_s}}$$

Where:

M=mutual inductance

f=frequency

R_p=primary resistance

R_s=secondary resistance

L_p=primary inductance

L_s=secondary inductance

K=coefficient of coupling

From the above equations, which are well understood to those skilled in the art, it is apparent that the conditions of critical couplings are not only dependent upon the space relationships between the coils 2 and 5 of the coupler TC and the distance between the transmitting loop 6 and the transmission line 1 but also involves the coupled positive resistance. In other words, the effect of the transmission line 1 and any adjacent metal bodies is the same as if positive resistance were added in the circuit of winding 5. Since there is no control over the re-

sistance of the transmission line and adjacent metal bodies coupled into the loop circuit, it is desirable to provide means to compensate for the positive resistance to that extent necessary to cause the positive resistance of such circuit to be equal to the positive resistance of the primary circuit dependent upon the mutual coupling to thereby cause the maximum transfer of signal energy.

- 10 It will also be observed that the inductive coupling between the transmitting loop 6 and the transmission line 1 is very loose, so that the coefficient of coupling will be very small. The particular degree of coupling cannot be changed 15 at will, nor is it continuously the same, since the mobile unit will be moving along a roadway adjacent to the transmission line at varying distances dependent upon the contour of the territory and the various circumstances involved 20 in the construction of the transmission line and the roadway.

Thus, it will be apparent that the resistance characteristics of the transmission line and the surrounding metal portions of the vehicle carrying the transmitter unit are quite out of control insofar as the selection of their values are concerned. On the other hand, the maximum transfer of energy cannot be effected between the primary winding 2 and the transmission line 1 unless the conditions of critical coupling are established between the primary winding 2 and the secondary winding circuit with the various resistances of the transmission line and the surrounding metal objects reflected therein. 35 Since the values of the reflected resistances are not controllable by ordinary means, it is proposed in accordance with the present invention to render such coupled in or reflected resistances controllable by the provision of suitable values 40 of negative resistance coupled into the output circuit to compensate for the undesired portions of the positive resistance in such circuits in such a way as to provide the required values of resistance necessary to give substantially the conditions required for critical coupling regardless 45 of the existing coupling.

To accomplish this purpose, it is proposed to provide the coils 3 and 4 connected to the oscillator OC with a tuning variable condenser C5. Suitable feed back energy is supplied to the grid through condenser C4 so that the oscillator OC is regenerative in character with the effect of negative resistance appearing across the outer terminals of the coils 3 and 4. This negative resistance, which can be governed in its value in accordance with the value of the variable series tank circuit resistor R4, acts to limit the amplitude of oscillations or regeneration of the amplifier OC, to insert the necessary value of negative resistance to cancel the proper amount of positive resistance present due to the above explained causes. This effective negative resistance is coupled into the coils 2 and 5 through the associated coils 3 and 4 and is effective to cause the organization to substantially approach the conditions of critical coupling between the output coil 2 and the transmission line 1.

The signal energy which is thus inductively produced in the transmission line 1 travels 70 throughout a considerable distance causing such transmission line to in turn produce lines of magnetic flux within a limited area of the line throughout such distance. These electro magnetic lines act upon the receiving loop 11 and produce a current in the winding 12 of the re-

ceiving coupler RC, which in turn induces potentials in the winding 13 of the coupler RC. This grid-cathode circuit is resonated by a variable condenser C8 to the carrier signal frequency and the energy therein is supplied to the control grid of the amplifying pentode tube RA. The plate circuit of this tube RA is connected through the winding 14, condenser C7 in multiple with variable resistor R3 and condenser C9 to provide an inductively coupled feed back to the grid circuit including the winding 13. This provides a regenerative amplifier so that the carrier signals received by winding 12 not only directly produce corresponding signals in the winding 15 but also produce a regenerative amplification in windings 13 and 14 which also acts to produce carrier signals in winding 15 of increased amplitude. The winding 15 is connected to the usual carrier frequency amplifier, demodulator and audio amplifier, so that its energy produced in accordance with the characteristics of the picked up energy cause the message to be reproduced by the loud speaker.

This regenerative amplifier RA has its regeneration controlled by the variable resistor R3 so that it will not reach the point of self oscillation but does act to in effect insert negative resistance in the coupling organization so as to cause the conditions of critical coupling to substantially exist between the transmission line 1 and the receiver input winding 15. In other words, the same principles of energy transfer between the transmission line 1 and the receiver are present in the coupling organization for the receiver unit as explained in connection with the transmitter unit. That is, in order to obtain the maximum transfer of energy between the transmission line 1 and the input winding 15, it is necessary to approach the conditions of critical coupling, and since due to the presence of metal structures and the inherent resistance of the transmission line, there is usually too much positive resistance coupled into the circuit so as to obtain the conditions of critical coupling. Thus, in accordance with the present invention the insertion of the regenerative amplifier RA acts to produce an effective negative resistance for cancelling the undesired portion of the positive resistance coupled into the circuit and thus substantially cause an improvement in the coupling organization.

The main difference between the receiver unit and the transmitter unit, is the fact that in the transmitter unit the element producing the negative resistance may be of the oscillatory type, which in its oscillations locks into and follows the carrier frequency as produced through the power amplifier; whereas in the receiver unit, since the received energy is of such small degree, it is impossible to provide a regenerative oscillator which will lock-in with the carrier frequency of the received signal so that the amplifier is of the controlled regenerative type which is maintained at a condition of operation optimum for the degree of coupling encountered. Thus, the negative resistance characteristics of a regenerative or oscillatory circuit are used in both the transmitter unit and receiver unit to compensate for an excessive amount of positive resistance coupled into the circuit in such a way as to improve the coupling characteristics as between the respective units and the transmission line carrying the transmitted signals.

In the drawings, the oscillator or regenerative amplifier OC has been shown as being of the well known Hartley type of oscillator. Also other con-

ventional circuit arrangements have been shown. However, it should be understood that the different circuit organizations may be changed and other well known circuit combinations employed to accomplish the same results, functions and purposes as disclosed herein without in any way departing from the invention. The purpose of the present invention is to be able to compensate for undesired positive resistance, which is especially troublesome in connection with transmitter and receiver units employed on railway cars and the like where large sections of metal are present adjacent the loop couplers, and by so doing, to improve the effectiveness of coupling to the adjacent transmission line. For this reason it is obvious that the present invention is especially adapted for railroad use where a transmitter or receiver unit may be located upon a locomotive or a steel car.

Having thus described a communication system of the inductive carrier current type as one specific embodiment of the present invention, it is desired to be understood that this form is selected to facilitate in the disclosure of the invention rather than to limit the number of forms which it may assume; and, it is to be further understood that various modifications, adaptations and alterations may be applied to the specific form shown to meet the requirements of practice, without in any manner departing from the spirit or scope of the present invention except as limited by the present claims.

What I claim is:

1. In a communication system of the carrier frequency type wherein a mobile transmitter is inductively coupled to a wayside conductor for the transmission of carrier signals over the conductor with such inductive coupling resulting in the reflection of the positive resistance of said conductor into said transmitter organization, said transmitter including a carrier frequency oscillator, means for frequency modulating the carrier frequency to constitute carrier signals, a power amplifier for amplifying said carrier signals and having an output circuit, a loop, a transformer having primary and secondary windings, said primary winding being connected to said output circuit of said power amplifier and said secondary winding being connected to said loop, a negative resistance device comprising a locking-in oscillator having an output circuit and a feed-back circuit, another winding on said transformer connected to the output circuit of said locking-in oscillator for inductively coupling its negative resistance effect into said output circuit of said power amplifier, said locking-in oscillator thereby locking into synchronism with said frequency modulated carrier signals, and manually adjustable means connected in the feed-back circuit of said locking-in oscillator for selecting its negative resistance output required to compensate for the positive resistance reflected into said output circuit of said power amplifier to that degree necessary to cause the maximum transfer of energy from the output circuit of said power amplifier to said wayside conductor.

2. In a carrier frequency type communication system having a mobile transmitter mounted on a movable vehicle constructed of metal parts, said transmitter comprising in combination, a loop inductively coupled to a line circuit, an oscillator, a modulator, and a power amplifier having its output circuit inductively coupled to said loop through a transformer coupling means for effecting the transfer of modulated signals to the line

circuit, said transformer coupling means at the same time coupling positive resistance from said line circuit and other objects into the output circuit of said power amplifier, a negative resistance device, another winding on said transformer coupling means connected to said negative resistance device for inductively coupling its negative resistance effect into the output circuit of said power amplifier to in part compensate for the positive resistance reflected into its output circuit through said transformer coupling means from said line circuit and the other objects adjacent said loop, and adjusting means connected to said negative resistance device and adjusted to the proper degree to cause the necessary output of said negative resistance device to compensate for that amount of positive resistance inductively coupled from said line circuit and other objects to cause the resultant resistance coupled into the output circuit of said amplifier to be substan-

tially equal to the positive resistance of the output circuit of said power amplifier to thereby produce the conditions of coupling for effecting a maximum transfer of energy between said power amplifier and the line circuit.
